UNITED STATES PATENT OFFICE.

RANSOM W. DAVENPORT, OF DETROIT, MICHIGAN, ASSIGNOR TO JEFFERY-DEWITT COMPANY, OF DETROIT, MICHIGAN, A CORPORATION OF MICHIGAN.

RAPID DECORATING FIRING FURNACE OR KILN.

Application filed December 27, 1920. Serial No. 433,328.

To all whom it may concern:

Be it known that I, RANSOM W. DAVENPORT, a citizen of the United States, and a resident of Detroit, county of Wayne, and 5 State of Michigan, have made an invention appertaining to Rapid Decorating Firing Furnaces or Kilns; and I do hereby declare the following to be a full, clear, and exact description of the invention, such as will 10 enable others skilled in the art to which it appertains to make and use the same, reference being had to the accompanying drawings, and to the characters of reference marked thereon, which form a part of this 15 specification.

My invention has for its object to provide a furnace or kiln for heat treating materials such as ceramic ware and metallic articles, whereby the temperature of the articles and the movement of reactive gases or vapors may be controlled to obtain maximum thermal economy and chemical efficiency, and high speed of production.

It particularly has for its object to provide in a furnace or kiln, a means whereby the ceramic ware may be continuously operated step by step to gradually increase the temperature of the ceramic ware and to gradually cool the ceramic ware while 30 being subjected to an atmosphere that will cause or permit certain modifications to take place in the ware or at the surface of the ware. It also has for its object to subject the ceramic ware to a regulatory temperature in close confining chambers while the ceramic ware is subjected to a moving vapor or gas that coacts with the heating means of the kiln to form the decorations in the glaze of the ceramic ware,

40 such as for example directing air in close proximity and in contact with the ceramic ware while being heated, whereby the temperature of the kiln is not only regulated but also the oxygen of the air is distributed 45 uniformly so as to cause or permit reaction at the proper times in the temperature changes to which the ceramic ware is subjected.

The invention also has for its object other 50 advantages and features which will appear from the following description and upon examination of the drawings.

The invention may be contained and performed in furnaces and kilns of different forms and for different purposes. To illus-

trate a practical application of the invention, I have selected a kiln as an example of such structures and shall describe it hereinafter. The kiln selected for purposes of illustration is shown in the accompanying drawings. 60

Figure 1 of the drawings is a longitudinal sectional view of a part of the kiln selected. Fig. 2 is a sectional view taken on the line 2—2 indicated in Fig. 1. Fig. 3 is a sectional view of the feeding mechanism. Fig. 4 is a top view of the feeding mechanism, the table top shown in Fig. 3 having been removed. Fig. 5 is one side view of the feeding mechanism and Fig. 6 is another side view of the feeding mechanism. Fig. 7 illustrates a broken view of the feeding block shown in Fig. 3 and Fig. 8 is a broken view of the positioning block, also shown in Fig. 3. Fig. 9 is an end view of the positioning block shown in Fig. 8. Fig. 10 illustrates somewhat diagrammatically the relation of the positioning block to the chambers of the kiln. Fig. 11 is a side view of the means for pneumatically controlling the feeding mechanism. Fig. 12 is a longitudinal sectional view of the pneumatic controller illustrated in Fig. 11. Fig. 13 is an end view of the controller illustrated in Fig. 11. Fig. 14 is an end view of the rotary valve that pneumatically controls the feeding mechanism. Fig. 15 is a sectional view taken on the line 15—15 indicated in Fig. 11. Fig. 16 is a diagrammatical view of the circuit of the heating element.

1, in Fig. 1, indicates a supporting frame 90 or standard, which may be of any form, for supporting the kiln and the feeding mechanism and parts associated therewith. 2 is a box preferably formed of sheet metal for enclosing the kiln. A plurality of long 95 tubular members 3 having a diameter slightly larger than the transverse dimension of the articles to be operated upon, are located in the box or container 2 and are surrounded by heat insulating material 4, such as infusorial earth. Within the heat insulating material and in close proximity to the bank of tubular members 3 is located an oblong frame 5 that surrounds the central portions of the bank of tubular members 3. Asbestos sheeting 6 surrounds the frame 5 and so as to enclose the space within the frame 5. A plurality of resistors 7 are located within the frame 5 and are supported in any suitable manner by the frame 5, while at the same time suit- 110

able insulators are located intermediate the resistors 7 and the frame 5 to prevent conduction of the electric current that passes through the resistors.

The resistors are located in parallel relation with the tubular members and are so placed in the frame 5 that each tubular member is located between a pair of resistors. Resistors are also located in proximity to the outer sides of the outer tubular members 3. By this arrangement a regulative heat of high temperature is produced within the confines of the asbestos sheeting 6 and within the oblong frame 5 and at the central portion of the bank of tubes 3, the heat being confined by the heat insulation 4. The heat insulating material 4 surrounding the tubes and particularly surrounding the grid formed by the resistors, is of considerable thickness which prevents practically the loss of any heat from the kiln by conduction. Moreover, the tubular members 3 are considerably longer than the grid.

The resistors are connected in series with each other and to the main line as indicated in Fig. 16.

The frame 5, containing and supporting the resistors, is connected to a plurality of rods 8 that are suspended from angle irons 9 that extend across the kiln. The ends of the angle irons 9 are supported at the sides of the kiln, as upon the angle irons 10 that extend along the sides of the kiln.

A fuse wire or member 11 may be located above the asbestos sheeting 6 or in any other position in proximity to the resistors 7, whereby the circuit of the resistors may be broken if the temperature increases above a certain limit. This operates to protect the grid from an over supply of current that may be conducted to the grid.

The tubular members 3 extend through the box or container 2 and the ends thereof fit closely the ends of the container 2. Ceramic bodies 73 may thus be passed through the tubular members 3 and consequently passed between the resistors 7 located in the central portion of the container 2 and finally delivered from the ends of the tubular members.

A suitable trough 12 may be provided for directing the ceramic bodies into a receptacle such as the receptacle 13.

While the ceramic bodies are being moved through the tubular members 3 and being subjected to the temperature changes, a vapor or gas is also directed through the tubular members 3 to raise and lower the temperature of the ceramic bodies and also to produce the requisite chemical reaction upon the decorating material. In the operation of the furnace I preferably direct the gas or vapor so that it will flow through the tubular members 3 in a direction opposite to that in which the ceramic bodies move as they progress through the tubular members

3. They will then be successively raised in temperature, maintained for a short period at the desired temperature and subsequently cooled by the moving gas or vapor while at the same time the active elements of the gas or vapor are brought into intimate relation with the ceramic bodies to cause or permit the necessary chemical reaction of the decorative material as it is being formed in or at the surface of the ceramic bodies. If oxygen is the desired reagent for forming the decorative material at the surface of the ceramic bodies, air may be directed through the ends of the tubular members and caused to flow in a direction reverse to that in which the ceramic bodies progress through the kiln and the flow thereof may be regulated so as to permit the ceramic bodies to rise and fall in temperature at the desired rates and be maintained at a desired temperature while at the same time the arrangement of the parts of the kiln is such that an intimate contact is brought about between the decorative material and the gaseous reagent. The air may be forced through the tubular members 3 or it may be drawn through the tubular members. Where air is used in the operation of the kiln, I find it preferable to draw atmospheric air through the tubes and I provide means for enclosing the ceramic body receiving ends of the tubular members. Where some other gaseous material is used to treat the decorative material, I find it preferable to force the gas through the tubes and direct it into the tubes at the delivering ends of the tubes. These ends of the tubes may also be enclosed so as to permit delivery of the articles treated and yet direct gaseous materials into the tubular members. In the form of construction shown in the drawings, air is drawn through the tubular members 3, the receiving ends of the tubular members being enclosed, together with mechanism for delivering the ceramic bodies to the receiving ends of the tubes, in a shell or casing that is connected with a suitable suction means.

14, in Fig. 3, is a pipe that is connected with a suction means, such as a centrifugal exhauster. The pipe 14 communicates with a chamber 15 located in casing which is connected with the tubular members 3, or covers the ends of the tubular members whereby the air is drawn through the bank of tubular members.

The tubular members, being slightly greater than the cross dimension of the ceramic bodies with which they are filled, comparatively a very small area of air stream through the tubular members is produced which brings the air into intimate and close contact with each of the ceramic bodies contained in each of the tubular members. Also the resistance to the air flow is great, while the degree of exhaustion or vacuous condi-

tion of the chamber 15 is relatively high. In other words, the quantity of air moving through the tubular members is small but the velocity is high. The movement of the 5 ceramic bodies through the tubular members 3 is step by step and intervals of time are permitted to lapse between each step by step movement. The ceramic bodies are thus raised in temperature at a uniform rate and 10 yet, comparatively, rapidly raised to the desired high temperature and maintained at that temperature during a number of such intervals and then gradually cooled by the air entering the delivering ends of the tubular members. The movement of the air 15 through the tubular members does not cause a loss of the heat produced by the heating element, but operates, in a more or less degree, to move the zone of high temperature 20 forward, that is, toward the receiving ends of the tubular members. The air entering, gradually cools the ceramic bodies as they are carried from the zone of high temperature and is itself raised in temperature to 25 that produced by the grid of resistors and on further movement this high temperature is conveyed to the ceramic bodies as they approach the zone of high temperature while it itself is being cooled, until it finds its exit 30 into the chamber 15. During this movement of the air relative to the ceramic bodies, the chemical reaction of the oxygen of the air on the decorative materials gradually takes place.

35 Where air is used, the reaction may be to oxidize certain ingredients of the decorative coating, such as the oil used as a vehicle for the pigment; and in this case it is important to oxidize and remove, by way of the air current, all carbonaceous matter and the products of its combustion before the ware reaches a temperature sufficient to flux the 40 decoration into the surface of the ware, else blackening of the decoration may result.

45 Other reactions may also be effected, or inhibited by the use of other reactive or inert gases which may be brought into intimate contact with all parts of the ware at any desired temperature within the range of activity of the ingredients of the decorative coating.

50 By this arrangement every particle of the air comes into contact with the ceramic bodies, whereby heat is transmitted one to the other without loss of thermal efficiency and also within the range of receptivity of the ingredient modified by the gaseous or vaporous atmosphere in contact with the ceramic body so that as the decorative materials or the ingredients thereof are modified by the agent of the gaseous or vaporous atmosphere, they are implanted or incorporated in the ceramic bodies at their surfaces.

55 The ceramic bodies may be inserted into the receiving ends of the tubular members 3 by any suitable means. I have, however, provided a means for inserting the ceramic bodies into the receiving ends of the tubular members and moving the ceramic bodies contained within the tubular members step by step towards the delivering ends of the tubular members. This means consists of a pneumatically operated piston 16 located in the cylinder 17. The piston 16 operates upon a cross-bar 18 provided with 60 a plurality of plungers 19 located in axial relation to the tubular members 3. Between the ends of the plungers 19 and the ends of the tubular members 3, is located a positioning block 20 which is pivotally supported, in 65 its relation to the enclosing walls of the chamber 15, by means of the centering pin 21 and the shaft 22. The shaft 22 is secured in the boss 23, formed on the end of the positioning lock 20, by means of the pin 24. The shaft 22 is pivoted in one of the 70 walls of the chamber 15 and is connected to the arm 25 to produce oscillatory movements of the block 20. The axis of the pin 21, and the shaft 22 is located in proximity 75 to the lower forward corner of the delivery block 20 and consequently the block 20 is tilted upwards so as to bring the lower side of the block 20 in line with the end of the tubular members 3 and of the feeding tubes 80 26. The forward side of the block 20 is beveled so as to permit the oscillatory movement of the block so as to bring the bottom of the block in line with the bottom of the tubular members 3 when in one position and 85 the feeding tubes 26 when in the other position.

90 The feeding tubes 26 are also located in the chamber 15 and are located in an inclined position so as to cause the ceramic bodies which are inserted therein to slide onto the block 20 from whence they are pushed by the plungers 19 into the tubular members 3 when the block 20 is lowered so 95 as to be placed in line with the plungers 19 and the tubular members 3. The position of the block 20 when in its lowered position may be regulated by means of the screws 100 105 74 on which the block rests when in its lowermost position.

110 The chamber 15 is, in the form of the invention shown, maintained at a reduced pressure and consequently any communication of the chamber 15 with the outside atmosphere would short circuit any moving air through the tubular members to the chamber 15. For this reason one or the other end of each of the inclined feeding tubes 26 is kept closed by a suitable door.

115 In the form of the invention shown I have provided a door 27 that covers the lower ends of the inclined feeding tubes 26. The door 27 is connected to the shaft 28 whereby the door 27 may be opened and closed at 120 proper intervals of time to permit ceramic 125 130

bodies that have been placed in the tubes 26 to fall into the block 20. The block 20 is provided with a plurality of troughs 29 which are adapted to register with the inclined feeding tubes 26 and the tubular members 3. When the door 27 is opened the block 20 is also raised and as the ceramic bodies pass from the ends of the inclined feeding tubes they enter the troughs 29 and 10 then immediately by their momentum and by the inclined position of the trough of the block 20 enter the ends of the tubular members 3. The block 20 is lowered and the plungers 19 are then moved forward so as to move all of the ceramic bodies within the tubular members 3 the length of each of the ceramic bodies. The shaft 28 is pivotally supported on the walls of the chamber 15 and is provided with an arm 30 which is 20 connected by means of a link 31 to a plunger bar 32 that is operated by a piston and cylinder 33, whereby the plunger bar 32 is moved rearward which pulls the link 31 rearward and the arm 30 downward and forward thereby causing rotation of the shaft 28. The shaft 28 is also provided with an arm 34 which is connected by means of a link 35 to the arm 25 located on the shaft 22. Simultaneously with the movement of the 30 arm 30, the shaft 22 is rotated, which causes the block 20 to rise and receive the ceramic bodies that are admitted upon opening of the door 27 and deliver them to the ends of the tubes 3.

35 The bar 32 is provided with a means for preventing rotation of the bar during its operation upon the link 31. In the form of construction shown the bar 32 has a square cross-section along a part thereof, that is located in the pillow 36 having the same cross section.

40 The decorative materials may be placed on the ceramic bodies in any way desired. I have shown somewhat conventionally a printing machine 37 that is located on the top of the table. The ceramic bodies are taken from the printing machine 37 and placed in a feeding block 38 which is disposed at a convenient position relative to the printing machine and below the table top. The block 38 is provided with a plurality of troughs 39 into which the ceramic bodies may be placed by hand or by any other suitable means. The troughs 39 are 45 located substantially in alignment with the ends of the inclined feeding tubes 26. A plurality of plungers 40 are located in line with the troughs 39 and when the plungers are moved forward the ceramic bodies placed within the troughs 39 are pushed into the upper ends of the inclined feeding tubes 26. They then slide down the inclined feeding tubes 26 until they slide into the ends of the tubular members 3 since the 50 door is opened substantially at the same

time or shortly after the beginning of the forward movement of the plungers 40.

55 The plungers 40 are connected to a cross-bar 41 located on ways 42 on which the ends of the bar 41 slide. The cross-bar 41 is connected with links 43 to arms 44 keyed to the shaft 45. One of the links 43 and one of the arms 44 are connected by means of a spring 46 with a link 47 through a slotted plate 47 and the screw 49. The spring tension as between the shaft 45 and the link 47 may be 60 adjusted by the slotted plate 47 and the screw 49, whereby the plungers 40 are yieldingly moved against the ceramic bodies located on the block 38. This is a protecting means for preventing the injury of operators when placing ceramic bodies in the troughs 39. The link 47 is connected to an arm 50 located on the non-rotative plunger bar 32. The operation of the piston 71 and cylinder 33 causes the operation of the plungers 40 and the block 20 and, at a very short interval thereafter, the opening of the door 27. The link 31 is located at right angles to the arm 30 when the door 27 is 65 closed and thus locks the door 27 in its closed position and prevents the reduced pressure in the chamber 15 from opening the door by the difference in pressures on the door.

70 Under certain conditions the feeding block 38 may be eliminated and the ceramic bodies placed in the block 20 directly, but for convenience of manipulation I have provided a means whereby the tubular members 3 may be located well below the top 72 of the table to provide space for the heat insulating bed in which the tubular members 3 are located and give room for inspection of the porcelain bodies or for other purposes on the table top. This is obtained 75 by keeping the table top at the proper working height. By providing the means for feeding the ceramic bodies to the positioning block, I have provided a means 80 whereby the ceramic bodies may be placed in recesses located in proximity to the table top and also in proximity to the delivering end of the printing machine, whereby the operative expense of feeding the porcelain bodies to the kiln is materially reduced.

85 The plungers 19, the plungers 40, the block 20 and the door 27 are operated at proper intervals of time to move or permit the movement of the ceramic bodies into the tubular members 3. The alternate 90 operation of the plungers 19 and 40 is obtained by means of the rotary valve 51 which is located on the shaft 52 and is rotated by any suitable means, such as by the gear wheels 53 that are connected with any 95 source of power, such as to an electric motor. The valve member 51 is keyed to the shaft 52 which extends through a housing 73. The shaft 52 has a reduced portion 54 leaving a space between the shaft 100

100

105

110

115

120

125

130

52 and the housing 73', while the valve 51 is provided with an opening 55 that alternately registers with openings 56 and 57 formed in the housing 73', and is also provided with a channel 58 which also alternately registers with the openings 56 and 57 and connects the openings 56 and 57 with the space formed between the shaft 52 and the housing 73'. The valve housing 73' is closed by a lenticular plate 59 that is connected by means of a pipe 60 with a source of compressed air. Air entering through the pipe 60 passes through the opening 55 and alternately enters the passageways 56 and 57. The passageway 56 is connected through the pipe 61 to the cylinder 17 for the operation of the piston 16 and the passageway 57 is connected through the pipe 62 with the cylinder 33, whereby the pressure is communicated through the valve member 51 to the pistons contained in the cylinders and the plungers 40 and 19 are operated alternately.

The valve member 51 rotates in the direction indicated in Fig. 14 and the channel 58 is located on the following side of the opening 55. The space between the shaft 52 and the housing is connected to the outside atmosphere by the passageway or opening 63. Air pressure is thus alternately produced in the pipes 61 and 62 and behind the pistons in the cylinders 17 and 33 and then exhausted, or reduced by the communication that is established through the channel 58 registering with the openings 56 and 57 and establishing a communication with the exterior atmosphere through the opening 63, immediately after the plungers have had opportunity to perform their forward movements. The pistons are connected to rods 64 that extend through plates 65 located on the ends of the cylinders. The rods 64 are provided with washers 66 that are secured on the rods by means of the nuts 67 and springs 68 are located intermediate the washers 66 and the plates 65 whereby the springs 68 will be compressed by the forward movement of the pistons when subjected to the air pressure admitted through the operation of the valve 51. When communication is established between the cylinders and the atmospheric air through the channel 58 located in the valve 51, the springs 68 operate to cause the pistons and the plungers to return.

This causes the plungers to reciprocate alternately and moreover causes the plungers 19 to move the ceramic bodies contained in the tubular members 3 forward the length of the ceramic bodies at intervals measured by the cycle of operations performed by the valve 51.

The valve 51 is so timed that the cycles are performed at such intervals, that opportunity is given for filling the feeding

block 38. It is also so timed relative to the length of the tubular members and the length of the heat element of the kiln and it is also so timed relative to the movement of the vaporous or gaseous material through the tubular members, that the temperature of the ceramic bodies will be raised, maintained and lowered and the temperature of the vaporous or gaseous materials by heat transmission will be raised, maintained and lowered so as to secure the desired decorative effect as described above.

I claim:—

1. In a furnace for heat treating bodies, a tubular member for containing bodies, means for heating the central portion of the wall of the tubular member, a plunger for moving the bodies through the tubular member, and means for directing a chemical reagent through the tubular member.

2. In a furnace for heat treating bodies, a tubular member for containing bodies, means for heating the central portion of the wall of the tubular member, a plunger for moving the bodies through the tubular member, and means for directing a chemical reagent through the tubular member in a direction reverse to that in which the bodies are moved.

3. In a furnace for heat treating bodies, an elongated tubular member, means for moving the bodies through the tubular member, means for heating the central portion of the walls of the tubular member, and means for directing a moving heat transferring material through the tubular member in a direction opposite to that in which the bodies are moved.

4. In a furnace for heat treating bodies, a tubular member, means for moving the bodies through the tubular member, a heater for heating a portion of the walls of the tubular member, and means for transferring the heat of the bodies leaving the said portion of the tubular member to the bodies entering the said portion.

5. In a furnace for heat treating bodies, a long tubular member, the interior having a cross sectional area slightly greater than the major cross sectional area of the bodies, means for heating the central portion of the walls of the tubular member, a plunger for moving the bodies and the tubular member the length of the bodies, and means for directing air through the tubular member.

6. In a furnace for heat treating bodies, a long tubular member, the interior having a cross sectional area slightly greater than the major cross sectional area of the bodies, means for heating the central portion of the walls of the tubular member, a plunger for moving the bodies in the tubular member the length of the bodies, means for directing air through the tubular member, a positioning block located in alignment

with the tubular member and with the plunger, a chute for directing the bodies to the positioning block, and means for closing the lower end of the chute.

5 7. In a furnace for heat treating bodies, a long tubular member, the interior having a cross sectional area slightly greater than the major cross sectional area of the bodies, means for heating the central portion of the 10 walls of the tubular member, a plunger for moving the bodies in the tubular member the length of the bodies, means for directing air through the tubular member, a positioning block located in alignment with the 15 tubular member and with the plunger, a chute for directing the bodies to the positioning block, means for closing the lower end of the chute, a feeding block located in alignment with the upper end of the chute, 20 and a plunger for moving the bodies from the feeding block to the chute.

8. In a furnace for heat treating bodies, a long tubular member, the interior having a cross sectional area slightly greater than 25 the major cross sectional area of the bodies, means for heating the central portion of the walls of the tubular member, a plunger for moving the bodies in the tubular member the length of the bodies, means for directing 30 air through the tubular member, a positioning block located in alignment with the tubular member and with the plunger, a chute for directing the bodies to the positioning block, means for closing the lower end of the 35 chute, a feeding block located in alignment with the upper end of the chute, a plunger for moving the bodies from the feeding block to the chute, and means for causing the alternate operation of the said plunger.

40 9. In a furnace for heat treating bodies, a plurality of tubular members, an electric heating grid surrounding the tubular members, a heat insulating material surrounding the tubular members and the grid, a plurality 45 of plungers for moving the bodies in the tubular members the length of the bodies.

10. In a furnace for heat treating bodies, a plurality of tubular members, an electric heating grid surrounding the tubular members, a heat insulating material surrounding the tubular members and the grid, the cross 50 sectional area of the interior of each of the tubular members being slightly larger than the major cross sectional area of the bodies, 55 and a plurality of plungers for moving the bodies the length of the bodies at intervals in the tubular members.

11. In a furnace for heat treating bodies, 60 a plurality of tubular members, an electric heating grid surrounding the tubular members, a heat insulating material surrounding the tubular members and the grid, the cross 65 sectional area of the interior of each of the tubular members being slightly larger than the major cross sectional area of the bodies,

a plurality of plungers for moving the bodies the length of the bodies at intervals in the tubular members, a shell for enclosing the ends of the tubular members, and means for directing air through the tubular mem- 70 bers.

12. In a furnace for heat treating bodies, a plurality of tubular members, an electric heating grid surrounding the tubular members, a heat insulating material surrounding the tubular members and the grid, the cross sectional area of the interior of each of the tubular members being slightly larger than the major cross sectional area of the bodies, 80 a plurality of plungers for moving the bodies the length of the bodies at intervals in the tubular members, a shell for enclosing the ends of the tubular members, means for directing air through the tubular members, 85 a positioning block having a plurality of troughs for placing the bodies in line with the plungers and the ends of the tubular members and located in the shell.

13. In a furnace for heat treating bodies, 90 a plurality of tubular members, an electric heating grid surrounding the tubular members, a heat insulating material surrounding the tubular members and the grid, the cross sectional area of the interior of each of the tubular members being slightly larger than the major cross sectional area of the bodies, 95 a plurality of plungers for moving the bodies the length of the bodies at intervals in the tubular members, a shell for enclosing the ends of the tubular members, means for directing air through the tubular members, a positioning block having a plurality of troughs for placing the bodies in line with the plungers and the ends of the tubular members and located in the shell, 100 a plurality of inclined chutes for directing the bodies to the positioning block, and a door for closing the ends of the chute and located in the shell.

14. In a furnace for heat treating bodies, 110 a plurality of tubular members, an electric heating grid surrounding the tubular members, a heat insulating material surrounding the tubular members and the grid, the cross sectional area of the interior of each of the tubular members being slightly larger than the major cross sectional area of the bodies, 115 a plurality of plungers for moving the bodies the length of the bodies at intervals in the tubular members, a chamber for enclosing the ends of the tubular members, means for directing air through the tubular members, 120 a positioning block having a plurality of troughs for placing the bodies in line with the plungers and the ends of the tubular members and located in the chamber, a plurality of inclined chutes for directing the bodies to the positioning block, a door for closing the ends of the chute and located in the chamber, 125 a feeding block having a plurality of troughs located in line with the 130

feeding chutes, and a plurality of plungers for moving the bodies from the feeding troughs into the chute.

15. In a furnace for heat treating bodies, 5 a plurality of elongated tubular members, an electric heating grid surrounding the tubular members, a heat insulating material surrounding the tubular members and the grid, the cross sectional area of the interior of 10 each of the tubular members being slightly larger than the major cross-sectional area of the bodies, a plurality of plungers for moving the bodies the length of the bodies at intervals in the tubular members, a chamber 15 for enclosing the ends of the tubular members, means for directing air through the tubular members, a positioning block

having a plurality of troughs for placing the bodies in line with the plungers and the ends of the tubular members and located in the 20 chamber, a plurality of inclined chutes for directing the bodies to the positioning block, a door for closing the ends of the chute and located in the chamber, a feeding block having a plurality of troughs located in line 25 with the feeding chutes, a plurality of plungers for moving the bodies from the feeding trough into the chute, and means for causing the two sets of plungers to operate alternately. 30

In testimony whereof I have hereunto signed my name to this specification.

RANSOM W. DAVENPORT.
